UNITED STATES PATENT OFFICE.

RUBEN DUVAL, OF SCAMMON, KANSAS.

RAIL-TIE.

1,147,623.

Specification of Letters Patent. Patented July 20, 1915.

Application filed October 23, 1914. Serial No. 868,271.

To all whom it may concern:

Be it known that I, RUBEN DUVAL, a citizen of France, residing at Scammon, in the county of Cherokee and State of Kansas, 5 have invented new and useful Improvements in Rail-Ties, of which the following is a specification.

The present invention relates to improvements in rail ties, the object being to provide 10 a tie wherein the rails will be supported and effectively locked against lateral movement without the employment of spikes or analogous devices, and the improvement resides in the construction, combination and operative arrangement of parts set forth in the 15 following specification and falling within the scope of the appended claims.

In the drawing: Figure 1 is a perspective view illustrating my improved tie, Fig. 2 is 20 a similar view illustrating one of the ties arranged to receive the rails, Fig. 3 is a horizontal sectional view taken flush with the rail receiving portions or rests for the rails, Fig. 4 is a longitudinal sectional view 25 on the line $x-x$ of Fig. 3, Fig. 5 is a sectional view on the line 5-5 of Fig. 4, Fig. 6 is a detail horizontal sectional view on the line 6-6 of Fig. 3, and Fig. 7 is a perspective view of a slightly modified form of 30 the tie.

In the reduction of my improvement to practice, as illustrated by the drawing, the improved tie includes a flat rectangular base plate 1 which may, and preferably, has 35 its central portion upon its underface provided with a transversely arranged reinforcing member 2. The plate or base 1 is preferably formed of metal, as is its reinforcement, and is also preferably of a 40 greater length than that of the ordinary tie, and the width of the plate may be correspondingly greater if desired.

Integrally formed centrally of the plate 45 adjacent the opposite ends thereof are vertically disposed members or bosses 3, each of said members having its upper end horizontally flat and being inclined inwardly from its said flat top. The outer ends are also preferably beveled downwardly, as indicated by the numerals 4, while the sides of the said enlargements or bosses 3, adjacent their connection with the base 1, are preferably grooved, as indicated by the numerals 5. The inner face of the top of each of 55 the members 3 is vertically straight and is

disposed at a right angle to the longitudinal plane of the boss and of the base 1. This vertically straight face, indicated by the numeral 6, intersects a horizontally disposed depression 7 which is formed with the boss 60 above the grooves 5, the lower face of said depression being horizontally straight, and the upper wall of the depression being beveled to correspond with the beveled upper face of the base flange of rails R which are adapted to be received within the said depression, while the vertical wall 6 is provided to be received within the fishing space of the rail between its base flange and head, and the rail proper rests upon the lower horizontally straight wall formed by the said depressions 7. The inner face of the boss 3 below the horizontal wall of its depression is beveled, as indicated by the numeral 8, the beveled faces of both of the bosses being arranged in the same angular direction. 75

The numeral 9 designates, what I will term, a lock member for the rails. The lock includes a base or bottom portion 10 which is centrally provided with a boss having an 80 opening for the reception of a pivot 11 which passes through the base 1 and its reinforcement 2, and is secured in any desired or preferred manner. The bottom 10 has its opposite ends formed with vertical enlargements or bosses 12, corresponding in size and shape with the bosses 3. The sides of the bosses are provided with grooves 13 which, when the lock is brought into register with the bosses 3, register with the 85 grooves 5, and the heads of the said bosses or enlargements 12 terminate flush with the bosses 3. The outer faces of the bosses below their heads are vertically straight, as indicated by the numerals 14, the said 90 straight faces intersecting inwardly disposed depressions 15, the said depressions including lower horizontally straight walls which are adapted to be arranged flush with the straight walls of the depressions 7, and the said outer faces or enlargements 12, from the straight walls of the depressions, are beveled in an opposite direction to the beveled portions 8 of the bosses 3, as indicated by the numeral 16, and these beveled faces 16 are adapted to abut with the beveled faces 7 of the bosses 3 when the lock 9 is swung to register with the bosses 3. The inner faces of the bosses or enlargements 12 are rounded 95 downwardly to the bottom plate 10, and 100 the outer faces of the bosses 3 are rounded upwardly to the top of the base 1. The 105 inner faces of the bosses 3 are rounded downwardly to the bottom plate 10, and the outer faces of the bosses 3 are rounded upwardly to the top of the base 1. The 110

the sides of said rounded inner faces are preferably beveled or inclined, as at 17.

It is to be understood that the upper walls of the depressions 15 are inclined, and by 5 first arranging the flanges of the rails R within the depressions 7, and by then swinging the lock 9 upon its pivot 11 until the beveled faces 16 of the lock contact with the beveled faces 8 of the bosses 3, the vertically 10 straight faces 14 of the enlargements 12 as well as the walls provided by the depressions will receive and effectively hold the rails upon the tie, as will, it is thought, be readily understood.

15 The enlargements 12, adjacent their outer ends, are each provided with a malleable or compressible bottom member 18, the same being provided to receive the force of impact of a hammer or similar device which 20 may be employed for swinging the lock 9 to bring the same into register with the bosses 3 and into locking position upon the rails, and the base 1 is provided with a transversely arranged slot or depression 19 25 which extends from one of its edges and terminates in a line flush with the side of the lock, while the base is further provided with a transversely extending opening 20 arranged below the said depression, and the 30 lower wall of the depression at its terminal is provided with a downwardly extending notch 21. Passing through the opening 20 is one arm of a spring 22, the second arm being arranged within the depression and 35 having its end bent upwardly, as at 23, above the base and its extremity downturned, as at 24, to be received within the notch 21. The spring is so arranged as to have its portion 23 contacted by the bottom 40 member of the lock when the lock is swung upon the plate, and to be forced thereby into the depression, after which the said spring will exert an upward tension so that its angular end 24 will engage with one side of 45 the lock and hold the said lock against accidental rotation.

In order to retain the spring 22 upon the tie as well as to provide means whereby the spring may be removed to be replaced by a 50 new spring when worn, I have provided one of the sides of the tie at the opposite walls of the depression 19, with threaded openings for the reception of a pair of headed threaded members 25, the heads of the said members engaging with the outer portion of the spring connecting their upper and lower arms.

In practice, after the rails have been arranged upon the tie, the base 1, as well as 60 the sides and ends of the bosses 3 and 12 up to the horizontal walls provided by the depressions in the said bosses, are embedded within the roadbed, and the said roadbed tamped around the tie and bosses. The 65 roadbed materially assists the spring in

holding the lock 9 in proper engagement with the bosses 3, and also prevents either a lateral, tilting or longitudinal movement of the tie, the bosses as well as the reinforcing member 2 of the base materially assisting 70 in the prevention of a movement of the tie in any direction.

It is to be understood that it is not absolutely necessary that all of the ties shall be 75 provided with the spring locking means, and ties not provided with this means, as illustrated in Fig. 7 of the drawings, may be arranged to support rails and positioned a suitable distance between ties provided with the said spring locks.

80 From the above description, taken in connection with the accompanying drawing, the simplicity of the device as well as the advantages thereof will, it is thought, be perfectly apparent to those skilled in the art 85 to which such inventions appertain without further detailed description.

Having thus described the invention, what I claim is:

1. A tie including a base, bosses arising 90 from the base adjacent the opposite ends thereof, said bosses each having its inner face recessed to provide a seat which agrees with one of the sides and approximately one-half of the base of a rail, and adapted 95 to receive the rail, a lock centrally pivoted to the plate and arranged between the bosses, said lock having its ends provided with upstanding enlargements, the outer faces of which being recessed to receive one 100 side and approximately one-half of the base flange of the rail, and means for holding the lock in register with the bosses to retain the rails upon their seats.

2. A tie including a base plate, bosses 105 arising from said plate adjacent the ends thereof, said bosses having their inner faces adjacent their tops provided with rail seats, a lock having its ends formed with rail engaging seats and centrally pivoted to the 110 base, and spring means for retaining the lock in register with the bosses.

3. A tie including a base plate which has its underface centrally reinforced, rail receiving members integrally formed but elevated above the tie and disposed to the sides thereof, a swinging lock adapted to engage with the inner faces of the rails and to contact with the rail receiving members upon the tie, means for automatically sustaining 115 120 the lock in engaging position with the rail receiving members and with the rails.

4. A tie including a substantially rectangular base which has its underface centrally enlarged, the tie being integrally 125 formed with rail seats elevated above and arranged adjacent the opposite ends of the tie, a centrally pivoted lock having its outer faces provided with rail engaging members, a spring element arranged upon the tie and 130

adapted to contact with one of the sides of the lock to retain the lock in register with the rail receiving members of the base.

5. A tie including a substantially rectangular base, bosses of a lesser width than the base and arranged centrally thereof at the opposite ends of the tie, said bosses having their sides channeled longitudinally, their outer edges curved downwardly to the 10 tie, their inner edges recessed adjacent the tops thereof to provide rail seats, the portions of the tie below the seats being beveled, a lock pivotally secured to the base between the bosses, said lock having its ends 15 provided with upstanding members, the inner edges of which being rounded downwardly to the base of the lock, their sides being channeled, their inner faces adjacent their tops recessed to provide rail seats and 20 their outer faces below the seats being beveled to agree with the beveled portions of the bosses, and means for securing the lock in register with the bosses.

6. A tie including a substantially rectangular base having its upper face adjacent its ends centrally provided with reduced upstanding members, the inner faces of which being recessed, to form rail seats,

a lock including a bottom member which is pivotally secured to the base centrally of the 30 enlargements of the base, said lock having its ends provided with upstanding members, the outer faces of which being recessed to provide rail engaging seats which are adapted to co-act with the seats of the tie, 35 the opposite faces of the lock, adjacent the ends being provided with malleable knobs, the base plate of the tie having a transverse depression which extends from one of its sides, and the side being provided with an 40 opening, a two-arm spring, one of the arms of the spring being arranged within the opening, the second arm being disposed over the recess and having its end elevated above the recess to contact with one of the sides 45 of the lock to retain the lock in register with the rail receiving enlargements of the tie, and removable elements for securing the spring upon the base of the tie.

In testimony whereof I affix my signature 50 in presence of two witnesses.

RUBEN DUVAL.
